Patented Dec. 29, 1925.

1,567,049

UNITED STATES PATENT OFFICE.

THOMAS T. GRAY, OF ELIZABETH, NEW JERSEY.

CHROMIUM SOAP.

No Drawing.

Application filed October 3, 1922. Serial No. 592,042.

To all whom it may concern:

Be it known that I, THOMAS T. GRAY, a citizen of the United States, and a resident of Elizabeth, county of Union, State of New Jersey, have invented an Improvement in Chromium Soaps, of which the following is a specification.

The present invention relates to detergents and more particularly to the manufacture of a soap suitable for general use and especially suitable for use in the preparation of shaving soap, cold cream, tooth paste, mouth washes and the like.

The invention has for an object to provide an improved detergent which will not have a disagreeable taste or odor, and which will not be irritating to the skin, eyes and other membranes of the body.

Another object is to provide a method of making the detergent.

The invention provides a soap which has fine lathering and detergent properties and yet does not possess the pronounced disagreeable taste or other objectionable properties of ordinary toilet soaps such as that of causing the eyes and skin to smart.

The harsh action of ordinary toilet soaps is probably due to the hydrolysis of the neutral soap during which process free alkali is liberated. This free alkali attacks the more sensitive membranes and causes soreness and smarting. I have discovered that a soap which is free of the objectionable irritating qualities above mentioned can be manufactured by the use of a chromium salt, such for example as chromium hydroxide or chromium carbonate. If the soap is made entirely of a chromium salt with a fatty acid or the like while soluble in water, it does not form a good lather. I have found, however, that if another soap having good lathering qualities, for example a good sodium soap, is combined with the chromium soap in suitable proportions a good toilet soap having the desirable qualities of both is obtained. Such compound soaps are furthermore particularly suitable for the preparation of shaving soap, tooth paste, cold cream and the like.

Chromium soap having the characteristics above indicated can be manufactured from the several suitable fatty acids and fatty materials used in the manufacture of sodium and potassium soap and by substantially similar processes. In the process se-

lected for description herein a fatty acid or other fatty material is melted and saponified with chromium hydroxide, which is slowly added in small portions. The hydroxide may be suspended in water and added in this condition. The mixture is heated during the reaction by any suitable means as, for example, by a steam coil. Chemical tests are made from time to time and when the neutral point is reached and the saponification is complete the adding of the chromium hydroxide or its equivalent is discontinued. The soap is then boiled down to the desired concentration.

If the compounds used in making the soap are sufficiently pure theoretical weights thereof may be used, these weights being calculated from the formula of the reaction, taking into account the molecular weights of the substances. For example, if a soap of chromium hydroxide and stearic acid were to be made the reaction would, it is believed, take place in accordance with the formula:

Since the molecular weights of chromium hydroxide and stearic acid are 103 and 284 respectively and since one molecule of chromium hydroxide combines with 3 molecules of stearic acid the two substances should be supplied in the ratio of 103 parts by weight of chromium hydroxide to 852 parts of stearic acid. While chromium hydroxide is particularly mentioned, the carbonate and other salts of chromium may be used in the manufacture.

The chromium imparts an attractive color to the soap but other suitable coloring matter and any desired flavoring, perfuming or medicinal agents may be added.

The soap made as above may be combined to advantage with sodium potassium or ammonium soaps or a mixture thereof to form a compound soap. The proportions of the chromium soap to the other soap or soaps may vary within wide limits. I have found that soaps in which the proportions vary between one part of chromium to five parts of other soap and one part of other soap to five parts of chromium soap retain in a satisfactory degree the properties of the separate soaps.

As a particular example I have found a soap containing approximately two parts of

neutral sodium soap, two parts of neutral chromium soap and one part of water to be neutral and tasteless and to possess fine lathering and detergent properties. Such a 5 soap is suitable for use in the preparation of shaving soap, shaving cream, tooth paste, and other toilet, medicinal or pharmaceutical preparations requiring a soap of this character.

10 I have described the compound soap as made by combining unmixed chromium soap with unmixed sodium or other soap but a similar product may be obtained by saponifying the fat with a suitable mixture of 15 chromium compounds and sodium potassium or ammonium compounds or a mixture thereof.

The particular description herein is merely 20 illustrative and is not intended to define the limits of the invention. Various modifications in both the product and the method of manufacture can be made within the scope of the invention.

I claim as my invention:

25 1. A detergent containing chromium

stearates combined with sodium and potassium stearates.

2. A detergent compound containing alkali metal soap and chromium soap in approximately equal proportions. 30

3. A detergent comprising a chromium soap and an alkali metal soap combined in a ratio of between 1 to 5 and 5 to 1, substantially as described.

4. A detergent comprising a chromium 35 soap and a sodium soap combined in a ratio of between 1 to 5 and 5 to 1 substantially as described.

5. A detergent comprising a compound chromium sodium soap comprising chromium and sodium soaps in approximately 40 equal proportions.

6. A tasteless detergent combining approximately two parts of chromium soap, two parts of alkali metal soap and one part 45 of water.

In testimony whereof, I have signed my name to this specification this 30th day of September, 1922.

THOS. T. GRAY.
